UNITED STATES PATENT OFFICE.

LAURENCE A. HAWKINS, OF SCHENECTADY, NEW YORK, ASSIGNOR TO
GENERAL ELECTRIC COMPANY, A CORPORATION OF NEW YORK.

BLOCK-SIGNAL SYSTEM.

No. 856,466.

Specification of Letters Patent.

Patented June 11, 1907.

Application filed January 11, 1907. Serial No. 351,834.

To all whom it may concern:

Be it known that I, LAURENCE A. HAWKINS, a citizen of the United States, residing at Schenectady, county of Schenectady, State 5 of New York, have invented certain new and useful Improvements in Block-Signal Systems, of which the following is a specification.

My invention relates to block signal systems for electrically-operated roads, and consists in the improvements in a system described in my former application, No. 342,455, filed November 8, 1906. In that application I described a block signal system 15 for electrically-operated roads having both rails conductively continuous for all currents (as distinguished from the systems employing inductive bonds for separating the rails into blocks), with transformers and signal controlling relays connected at intervals 20 across the rails, and means controlled by an approaching train for closing the circuit of a transformer ahead of a train. The system was arranged to operate on the normal-danger plan, since with this method of operating the signals the transformers may be 25 normally open-circuited and economy of current secured. In order to close the circuit of a transformer ahead of a train, I made 30 use, in my former application, of an electromagnet or relay connected to a short insulated rail-length, which served as a contact to be closed by a train passing over it. For such insulated section insulating rail-joints 35 are, of course, required, and these joints are objectionable with respect to maintenance, since they wear out rapidly in service and must be frequently replaced.

The object of my present invention is to 40 provide means for closing the circuit of a transformer ahead of a train, without employing any insulated joints whatever, and without resorting to circuit-closers mechanically operated by a train. I secure 45 this result by connecting at intervals across the rails sources of low-voltage high-frequency current with relays in circuit with the sources controlling the transformers. These sources may be of sufficiently low 50 voltage and sufficiently high frequency, so that when they are placed at some distance from any other devices connected across the rails the current-flow from these sources is small, but when a train is directly over one

of them, the current in that source rises to 55 several times its normal value. This rise of current I utilize to actuate the relay controlling the transformer circuit.

My invention will best be understood by reference to the accompanying drawing, 60 which shows diagrammatically a block signal system arranged in accordance with my invention.

In the drawing, A represents the rails of an electric road, both of which are made conductively continuous, so as to serve as return conductor for the power-current. 65

B represents the third rail, or other supply conductor, connected to one terminal of the power-generator C; the other terminal of 70 which may be connected to the rails A through the differential choke-coil c. This generator may furnish either direct current or low-frequency alternating current.

D represents a high-frequency alternating 75 current generator which furnishes the power for the signal circuits.

E E' represent transformers, the primaries of which are connected to the transmission wires d, which extend from the generator D along the track, and the secondaries of which are connected across the rails through a small resistance e, which may be employed to limit the flow of current from the transformer when short-circuited by a train. The 80 transformers E E' are normally open-circuited on either their primary or secondary side. I have shown the secondary open-circuited, but it will be understood that if the relative values of current and voltage 85 make it preferable, the primary may be open-circuited, instead.

F F' represent track relays responsive only to alternating-current, if direct current is used for the power circuits; or to alternating 95 current of a predetermined frequency only, if alternating current is used for the power circuits. I have illustrated a relay of the induction type having a short-circuited secondary member f, carrying the relay contacts, and co-operating windings, one of which, f¹, is connected across the track, and the other, f², supplied from the line wires d through any phase-controlling device, such as the condenser f³, arranged to 100 give a phase-displacement between the currents in the two windings f¹ and f².

G G' represent electromagnets controlling

the circuits of transformers E and E' and relays F and F', respectively, by means of a normally-open contact in series with the transformer, and a normally-closed contact 5 in series with the relay. The electromagnets G G' are shown supplied from batteries g, g', but any other suitable source of current may be employed for these magnets. For instance, if the magnets are arranged to operate on alternating current, they may be supplied directly from the transformers E E'. These magnets are normally de-energized.

H H' represent signals provided with any suitable operating mechanisms indicated dia- 15 grammatically by the solenoids I I'. The signals are normally at danger with their operating mechanisms de-energized.

i represents any suitable source of current for the operating mechanism.

20 Each signal is provided with contacts h, h¹ and h² for purposes that will be hereinafter explained.

The system, as thus far described, is identical with that disclosed in my former application, above referred to, but in place of the 25 short rail section of my former application, I provide transformers K K', and relays L L' in circuit with the transformers. These transformers are connected on their primary 30 sides to the line wires d, and their secondaries, which are connected across the rails, are designed for a low voltage. Since the frequency of the voltage impressed by these 35 transformers on the rail is high, and since the voltage of the transformers is low, the amount of current which will flow from the transformers to the nearest signal devices connected across the rails will be very small if the transformer is at some distance from the 40 nearest signal devices. In order to reduce this flow to a minimum, the transformer may be placed in the middle of a block, though a position at the exact center of a block is not necessary if the voltage is sufficiently low. 45 If the transformers K K' are some distance away from the nearest relays F F', and if the transformer voltage is sufficiently low, the relays will not be affected by the voltage impressed on the rails by these transformers, 50 but as a further safe-guard, the transformers may readily be arranged to supply to the rails a voltage which, regardless of its amount will not affect these relays at all. This result might be secured by supplying to the 55 transformers K K' a frequency different from that supplied to transformers E E' and relays F F', but a simpler arrangement for securing the same result consists in placing the condensers k k' in series with the trans- 60 former primaries so as to shift the phase of the voltage supplied by these transformers to the track. In this way not only may the relays F F' be made independent of the current supplied by the transformers K K', 65 but also the relays L L' may be made inde-

pendent of the current supplied by trans- formers E E'.

When no trains are running, the conditions of the circuits are as shown in the drawing. The transformers E E' are open-circuited at the contacts of the electromagnets G G'. The transformers K K' have their circuits closed, but for reasons above explained, the amount of current flowing through their secondaries is small, so that relays L L' are not sufficiently energized to close their contacts. When a train reaches transformer K, it short-circuits the transformer through the track winding of the relay L, thereby greatly increasing the current 70 in the transformer and relay, so as to cause the relay to close its contact. This establishes a circuit from the lower rail A through the contacts of relay L, battery g', electromagnet G', upper rail A, and through the 80 axles of the train to the lower rail. Magnet G' is, consequently, energized and draws up its armature, closing a maintaining circuit for itself, which may be traced from the lower terminal of battery g' through contacts h' of 90 signal H, through upper armature of magnet G', and through the magnet winding to the upper terminal of battery g'. Consequently, although relay L soon opens its contacts again, as the train passes beyond it, electromagnet G' remains energized. Now, let it be assumed that magnet G has been energized in the manner described above, and that a train is approaching, as indicated by the arrow. The energization of magnet G has opened the 100 circuit of track winding f' of relay F at the back contact of the lower armature of magnet G, and has closed the secondary circuit of transformer E at the front contact of that armature. Transformer E consequently im- 105 presses an alternating current voltage across the track-rails, and if the block between transformer E and relay F' is unoccupied, relay F' will be energized, closing its contacts and thereby energizing the operating mechanism I 110 of signal H, which draws the signal to clear position. In the movement of the signal to clear, movable contact h is brought into engagement with its stationary contacts, thereby closing a second circuit for transformer E. 115 After this circuit is closed, contacts h¹ and h² leave their stationary contacts, thereby breaking the maintaining circuit of magnet G, and at the same time introducing a second break into the track winding of relay F. 120 Magnet G consequently drops its armatures, but the circuit of transformer E is main- 125 tained closed, and the circuit of the track winding of relay F is maintained open at the signal. This condition of the circuits con- 130 tinues until the train, in passing signal H, comes close enough to transformer E to pull down its voltage sufficiently to de-energize relay F'. When this occurs, relay F' opens its contacts, allowing signal H to go to danger; 130

thereby restoring all the circuits to their original condition.

It will be noted that a conductor is extended back from relay L to electromagnet G. The purpose of this is to insure the de-energization of magnet G in case signal H should not clear. If the clearing of the signal alone were relied upon for de-energizing magnet G by breaking its maintaining circuit, this magnet would not be de-energized in case the signal mechanism should fail so as to prevent the signal H from clearing, and consequently the preceding signal would be prevented from clearing; but by means of the conductor above mentioned, if signal H should fail to clear, magnet G will be de-energized when the signal reaches relay L, since this relay, in closing its contacts, short-circuits magnet G through the contacts of relay L, the train axles, and the upper rail A; thereby causing the magnet to drop its armatures.

I do not desire to limit myself to the particular construction and arrangement of parts here shown, but aim in the appended claims to cover all modifications which are within the scope of my invention.

What I claim as new and desire to secure by Letters Patent of the United States, is,—

1. In combination with an electrically operated road having both rails conductively continuous for all currents, normally open-circuited transformers adapted to impress an alternating voltage in the track rails, normally closed circuited sources of voltage connected across said rails, means in circuit with said sources responsive to the approach of a train to close the circuit of a transformer ahead of the train, and signal controlling devices responsive to the alternating voltage impressed on the rails by the transformers when their circuits are closed.

2. In combination with an electrically operated road having both rails conductively continuous for all currents, transformers adapted to impress an alternating voltage on the track rails, normally closed circuited sources of voltage connected across said rails, relays in circuit with said sources controlling the circuits of said transformers, and signal controlling devices responsive to the voltage impressed on the rails by the transformers when their circuits are closed.

3. In combination with an electrically operated road having both rails conductively continuous for all currents, transformers and signal controlling relays connected at intervals across said rails, said transformers being normally open-circuited, and means connected across said continuous rails at points be-

tween the transformers and relays responsive to the approach of a train for closing the circuit of a transformer ahead of the train.

4. In combination with an electrically operated road having both rails conductively continuous for all currents, transformers and

signal controlling relays connected at intervals across said rails, said transformers being normally open-circuited, normally closed-circuited sources of voltage connected across said rails at points between the transformers and relays, and devices in circuit with said sources controlling the circuits of said transformers.

5. In combination with an electrically operated road having both rails conductively continuous for all currents, transformers and signal controlling relays connected at intervals across said rails, said transformers being normally open-circuited, normally closed circuited sources of voltage connected across said rails at points between the transformers and relays, and devices in circuit with said sources controlling the circuits of said transformers, the voltage impressed on the rails by said sources being different in character from that of said transformers and ineffective for operating said signal controlling relays.

6. In combination with an electrically operated road having both rails conductively continuous for all currents, transformers and signal controlling relays connected at intervals across said rails, said transformers being normally open-circuited, normally closed circuited sources of voltage connected across and relays, and devices in circuit with said said rails at points between the transformers sources controlling the circuits of said transformers, the signal controlling relays being responsive only to current from said transformers.

7. In combination with an electrically operated road having both rails conductively continuous for all currents, sources of low voltage high-frequency current connected across said rails at intervals, normally open-circuited transformers connected to the rails, means in circuit with said sources for closing the circuits of said transformers, and signal controlling relays responsive to the alternating voltage impressed on the rails by the transformers when their circuits are closed.

8. In combination with an electrically operated road having both rails conductively continuous for all currents, transformers connected at intervals across the rails, normally open contacts in series with said transformers, electromagnets controlling said contacts, sources of low-voltage high-frequency current connected across the rails, relays in circuit with said sources controlling said electromagnets, and signal controlling relays responsive to the voltage impressed on the rails by said transformers when said contacts are closed.

In witness whereof, I have hereunto set my hand this 9th day of January, 1907.
